Primary Examiner — Richard Edgar*Assistant Examiner* — Alexander J David(74) *Attorney, Agent, or Firm* — Tsz Lung Yeung(57) **CLAIM**

The ornamental design for a check valve part for automobile as shown and described.

DESCRIPTION

FIG. 1 is a perspective view of a check valve part for automobile showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a perspective view thereof, shown in an in-use condition.

The broken lines in the drawings illustrate portions of the check valve part for automobile that form no part of the claimed design.

1 Claim, 9 Drawing Sheets(56)
